ESCAPEMENT DEVICE FOR PAPER CARRIAGES OF TYPEWRITERS

Fritz Eibert, Munich, Germany, assignor to
Robert Wolff, Basel, SwitzerlandApplication May 6, 1933, Serial No. 669,706
In Germany November 26, 1932

10 Claims. (Cl. 197—87)

The invention relates to an escapement device for paper carriages of type-writers.

In the well-known escapement devices for paper carriages of type-writers, the type reaches the platen at the moment, at which a change from the retaining to the displacement-pawl in front of the retained tooth of the ratchet wheel occurs. This change does not take place without any movement and vibration of the paper carriage so that the stroke of the type does not occur during a period in which the paper-carriage is absolutely at a standstill. Consequently, the impression of the type is not sharp and the spaces between the letters become uneven according to whether the touch of the key is weak, strong, slow or quick.

A further essential disadvantage consists in the fact that the ratchet wheel which moves by the action of the return main spring, strikes with its teeth on leaving the retaining-pawl, on to an inclined surface of the displacement-pawl and thereby offers a resistance to the operated type-lever immediately before the impression of the type. In order to avoid a diminution in the force of the stroke, a stronger touch on the keys is necessary for overcoming this resistance, which in time tires the operator.

The present invention avoids these disadvantages by an escapement device which makes any vibration or movement of the paper carriage impossible before and during the stroke of the type, and, moreover, offers no resistance to the operated type-lever.

These advantages are accomplished in such a way that a pawl which retains the paper carriage in its initial position before every touch of the key, remains in contact with the tooth of the escapement device during the period of the forward movement of the type-lever up to the completed stroke of the type, and that this contact is only then removed when the stroke of the type on the platen has taken place. For this purpose, the retaining-pawl is arranged pivotally, for example, parallel to its holding surface and it is kept in its initial position by a retaining spring. The power of the spring and the weight of the pawl are both dimensioned in such a way that the pawl, on the cessation of the movement of the pawl-bearer, moves further on to release the tooth retained by it. The release of the retained tooth after the stroke of the type on the platen can also be obtained by providing the universal bar with a weight which continues in its movement after the bar has come to a standstill and acts thereby upon the pawl-bearer or upon the

retaining-pawl in such a manner that the retained tooth is released.

In order to bring back into their initial position all parts moved in the one direction by a touch on the key without any spring action being necessary, the inclined surface of the displacement-pawl is arranged in such a manner that the tooth which strikes this inclined surface after being released by the retaining-pawl, acts on the pawl-bearer and thereby on all such parts as are moved by the touch on the key and returns the parts into their initial position. The tooth released by the pivotal retaining-pawl, strikes with force onto the inclined surface of the displacement-pawl so that the return movement of all parts, including the operated type-lever, occurs with considerably increased rapidity. By this means the speed of type-writing is increased and the striking of the types one upon the other is prevented. The touch of the keys becomes lighter and the power of impression greater. Additionally, the escapement mechanism is exposed to less wear and interruptions are avoided to a large extent.

It is of advantage to limit the movement of the operating-lever in order that the movement will cease when the type-lever with its type has just about reached the printing point. The remaining short movement up to the spot of impression can be effected by the type-lever by its own motor force, as it cannot be met by any impediments by the escapement mechanism, for the toothed wheel remains completely locked until after the impression of the type has taken place, and any influence on the part of the return spring is prevented for the time being.

In the drawing in which several examples are diagrammatically shown, is,

Figure 1 an escapement device in which the retaining-pawl is pivotally arranged on the pawl-bearer,

Figure 2 a plan-view of the pawl-bearer with the retaining-pawl and displacement-pawl in cross-section;

Figure 3 illustrates a modified embodiment of the invention.

In the various illustrations, similar parts are designated by the same references.

When the key is operated, the type-lever A is set in motion by the well-known connection, and strikes with its head B against the universal-bar 1. In Figure 1, the universal-bar 1, is pivotally mounted on the axis 2. The lug 4 is a part of the universal-bar 1 and is pivotally arranged at 3. The lug 4 has an abutment 5. The pawl-bearer 50

7 is movably mounted on the axis 8. The stop of the pawl-bearer 7 is delimited by the set-screws 9 and 10. The retaining-pawl 12 is mounted on the pawl-bearer 7, the former being pivotally mounted on its axis 13, and is loaded with a weight 14. The displacement-pawl 15 having an inclined surface, is also fixed on the pawl-bearer 7. 11 is a tooth of the ratchet wheel. A spring 16 serves the purpose of holding the universal-bar in its initial position. The pawl-bearer 7 is kept in its initial position by the spring 17, and the pivotal pawl 12 is kept in its initial position by a spring 18.

The action of the arrangement according to Figure 1 is as follows:

When the type-lever A is operated, it moves the universal-bar 1 in the direction of the arrow. After a certain movement of the type-lever, the universal-bar 1 strikes with its abutment 5 against the screw 6 of the pawl-bearer 7, the movement of which can be delimited by the set-screws 9 and 10. When the pawl-bearer in its movement strikes upon the set screw 9, the tooth 11 of the ratchet wheel still touches at this moment with a small part the retaining-pawl 12, being pivotally arranged on its axis 13.

After the universal-bar 1 and the pawl-bearer 7 has come to a standstill, the retaining-pawl 12 continues its movement by means of its weight 14, thereby releasing the tooth 11 of the ratchet wheel. The tooth 11 then strikes with force onto the inclined surface of the displacement pawl 15. By this means, all parts set into action by the touch of the key as well as the type-lever are moved back into their initial position.

In the arrangement shown in Figure 3, the pawls 12 and 15 are directly connected with the universal-bar 1, whereby the retaining-pawl 12 is pivotably arranged. The type-lever A forced against the platen of the type-writer moves the universal-bar 1 for such a distance that the bar with its abutment 22 strikes upon an abutment 21. This movement is shared by all parts arranged on the universal-bar. However, the tooth 11 of the ratchet wheel has not been set free from the retaining-pawl 12 by this movement. As, however, the retaining-pawl 12 with the aid of its weight 14 continues its movement around its axis 13, the tooth 11 of the ratchet wheel is released. The tooth 11 strikes upon the inclined surface of the displacement-pawl 15 lying before it, and by this means forces the universal-bar and the operated type-lever back into its initial position. A spring 18 holds the retaining-pawl 12 in its initial position.

What I claim is:—

1. In an escapement device for the paper carriage of a typewriter, the combination which comprises means for retaining said paper carriage including a ratchet having teeth associated with said carriage and a removable and weighted retaining pawl, said retaining pawl being capable of limited movement on actuation of a type and of engaging a tooth of said ratchet up to completed impression of a type and due to its inertia imparted by said weight being capable of continuing its movement and of disengaging said tooth after said type has been impressed.

2. In an escapement device for the paper carriage of a typewriter, the combination which comprises a ratchet having teeth associated with said paper carriage, means for retaining said paper carriage including a movable retaining pawl being capable of limited movement on the actuation of a type and of engaging a tooth of

said ratchet up to completed impression of said type, and having sufficient inertia to cause continuation of its movement and to disengage said tooth after said type has been impressed, and means for returning said pawl into its initial position. 5

3. In an escapement device for the paper carriage of a typewriter, the combination which comprises a ratchet having teeth associated with said paper carriage, means for retaining said paper carriage including a movable retaining pawl being capable of limited movement on the actuation of a type and of engaging a tooth of said ratchet up to completed impression of said type, and having sufficient inertia to cause continuation of its movement and to disengage said tooth after said type has been impressed, and means for returning said retaining pawl into its initial position, said returning means including a displacement pawl operatively associated with said retaining pawl and having an inclined surface adapted to slidably receive said disengaged tooth. 10 15 20

4. In an escapement device for the paper carriage of a typewriter, the combination which comprises a universal bar adapted to be actuated by a type lever of the typewriter during a stroke thereof, a movable pawl bearer adapted to be acted upon by the forward movement of said universal bar during a stroke of the type lever, a retaining pawl pivotally mounted on said pawl bearer engaging a tooth associated with the carriage of the typewriter, said retaining pawl having sufficient inertia to continue its movement after the completion of the forward movement of the universal bar and to disengage the tooth 30 35 40 after completion of the stroke of the type lever, and a displacement pawl mounted on said pawl bearer having an inclined surface adapted to slidably receive said disengaged tooth and to return said pawl bearer and said retaining pawl into their initial position.

5. In an escapement device for the paper carriage of a typewriter having types and a universal bar, the combination which comprises a ratchet having teeth associated with said paper carriage, a retaining pawl pivotally mounted on said universal bar, said retaining pawl being capable of limited movement on actuation of said universal bar by impression of a type and of engaging a tooth of said ratchet up to completed 45 50 55 impression of a type, and having sufficient inertia to cause continuation of its movement and to disengage said tooth after said type has been impressed.

6. In an escapement device for the paper carriage of a typewriter having types and a universal bar, the combination which comprises a ratchet having teeth associated with said paper carriage, a retaining pawl pivotally mounted on said universal bar, said retaining pawl being capable of limited movement on actuation of said universal bar by impression of a type and of engaging a tooth of said ratchet up to completed impression of a type, and having sufficient inertia to cause continuation of its movement and to disengage 60 65 70 75 said tooth after said type has been impressed, and a displacement pawl rigidly mounted on said universal bar and having an inclined surface adapted to slidably receive said disengaged tooth and to return said universal bar and said retaining pawl into their initial position.

7. An escapement device for typewriters and the like which comprises a universal bar adapted to be operated on by a type lever of the typewriter during a stroke thereof, a movable pawl bearer 75

adapted to be acted upon by the forward movement of the universal bar during a stroke of the type lever, a retaining pawl pivotally mounted on said pawl bearer engaging a tooth associated with the carriage of the typewriter said retaining pawl having sufficient inertia to continue its movement after the completion of the forward movement of the universal bar whereby the tooth is released after the completion of the stroke of the type lever.

8. In an escapement device for typewriters having a universal bar operatively associated with a type lever and a ratchet wheel having teeth, the improvement which comprises a reciprocating retaining pawl successively engaging said teeth adapted to be acted upon by the forward movement of the said universal bar during a stroke of the type lever and to continue its forward movement after the completion of the forward movement of the said universal bar whereby a tooth is released by the retaining pawl after the completion of the stroke of the type lever.

9. In an escapement device for typewriters having a universal bar operatively associated with

a type lever and a ratchet having teeth, the improvement which comprises a pivoted pawl bearer adapted to be actuated by said universal bar, a retaining pawl successively engaging said teeth pivotally mounted on said pawl bearer, said pawl being weighted so as to continue its movement after the completion of the forward movement of the said universal bar and release the engaged tooth after the completion of the stroke of the type lever.

10. An escapement device for typewriters and the like which comprises a universal bar actuated by a type lever of the typewriter during the stroke of the said lever, a reciprocating pawl bearer, a retaining pawl movably mounted thereon adapted to receive an impulse from the universal bar, and a ratchet having teeth successively engaging said retaining pawl said retaining pawl having sufficient inertia to continue its motion and release the ratchet after the completion of the stroke of the type lever, and means for returning the elements into their initial position.
